(57) **CLAIM**

The ornamental design for an inhaler having cover, as shown and described.

DESCRIPTION

FIG. 1 is a front view of a first embodiment of an inhaler having cover.

FIG. 2 is a left side view of the inhaler having cover shown in FIG. 1.

FIG. 3 is a right side view of the inhaler having cover shown in FIG. 1.

FIG. 4 is a rear view of the inhaler having cover shown in FIG. 1.

FIG. 5 is a top view of the inhaler having cover shown in FIG. 1.

FIG. 6 is a bottom view of the inhaler having cover shown in FIG. 1.

FIG. 7 is a bottom-left front perspective view of the inhaler having cover shown in FIG. 1.

FIG. 8 is a rear perspective view of the inhaler having cover shown in FIG. 1.

FIG. 9 is a front view of a second embodiment of an inhaler having cover.

FIG. 10 is a left side view of the inhaler having cover shown in FIG. 9.

FIG. 11 is a right side view of the inhaler having cover shown in FIG. 9.

FIG. 12 is a rear view of the inhaler having cover shown in FIG. 9.

FIG. 13 is a top view of the inhaler having cover shown in FIG. 9.

FIG. 14 is a bottom view of the inhaler having cover shown in FIG. 9.

FIG. 15 is a bottom-left front perspective view of the inhaler having cover shown in FIG. 9; and,

FIG. 16 is a rear perspective view of the inhaler having cover shown in FIG. 9.
